[57] CLAIM

The ornamental design for gunsmith tool set, as shown and described.

DESCRIPTION

FIG. 1 is a top, side perspective view of a gunsmith tool set showing our new design, the opposite sides of the handles being identical to the sides shown;

FIG. 2 is a top plan view thereof; and

FIG. 3 is a side elevational view of the top portions of the tool set, the shafts and handles being omitted for convenience of illustration.

The opposite side of the design shown in FIG. 1 is substantially the same as that side shown.
